UNITED STATES PATENT OFFICE.

DANIEL MARION MORGAN, OF ATHENS, TEXAS.

DESIGN FOR A TOOL.

SPECIFICATION forming part of Design No. 31,632, dated October 10, 1899.

Application filed August 28, 1899. Serial No. 728,798. Term of patent 7 years.

To all whom it may concern:

Be it known that I, DANIEL MARION MORGAN, a citizen of the United States, residing at Athens, in the county of Henderson and State of Texas, have invented and produced a new and original Design for Tools, of which the following is a specification.

This invention relates to a new and useful design for tools.

10 The essential features of the design reside in the central arch having exterior cylindrical projections and from which also extend arms provided with angular terminals, one of the terminals having a V-shaped recess and tapered and the other rounded and terminating in a slightly-enlarged circular face.

In the drawings, Figure 1 is a perspective view of a tool embodying the design. Fig. 2 is a bottom plan view of the same.

15 20 Similar numerals are employed to indicate like parts in the views.

The numeral 1 designates a central arch, from which extend cylindrical projections 2, having an inclination inwardly toward each

other. The projections 2 stand out from the 25 crown 3 of the arch, and the opposite sides 4 of the latter diverge and merge into oppositely-extending straight arms 5 and 6, the arm 5 having its outer extremity in a plane approximately at a right angle thereto and 30 tapered, as at 7, to an edge extremity 8. This part of the arm is also formed with a V-shaped recess 9. The outer extremity 10 of the arm 6 is cylindrical in form, with a slightly-enlarged terminal 11, which has a circular face 35 12, as clearly shown by Fig. 2. The extremity 10 is also substantially in a plane at right angles to its arm 6.

What is claimed as new is—

The design for a tool herein shown and de- 40 scribed.

In testimony that I claim the foregoing as my own I have hereto affixed my signature in the presence of two witnesses.

DANIEL MARION MORGAN.
